LIGHTING FIXTURE

Ross Lowell, 60 Riverside Drive, New York, N.Y. 10024

Filed June 19, 1967, Ser. No. 7,522

Term of patent 14 years

(Cl. D48—20)

FIG. 1.

FIG. 2.

FIG. 3.

FIG. 4.

FIG. 5.

FIG. 6.

FIG. 7.

FIG. 8.

FIG. 9.

FIG. 1 is a side elevational view of the lighting fixture of the present invention;

FIG. 2 is a front view thereof;

FIG. 3 is top plan view;

FIG. 4 is a bottom plan view;

FIG. 5 is an elevational view of the opposite side of said lighting fixture from that shown in FIG. 1;

FIG. 6 is a rear view thereof;

FIG. 7 is an exploded side elevation of a modified form of the fixture shown in FIG. 1 wherein the difference resides in the addition of a barn door attachment;

FIG. 8 is a front elevation of the modified form; and FIG. 9 is a top plan view of the modified form.

I claim:

The ornamental design for a lighting fixture, as shown and described.
